UNITED STATES PATENT OFFICE.

LONGLEY LEWIS SAGENDORPH, OF CINCINNATI, OHIO, ASSIGNOR OF ONE-HALF TO HARLAN P. LLOYD, OF SAME PLACE.

DESIGN FOR A METALLIC CEILING.

SPECIFICATION forming part of Design No. 19,155, dated June 11, 1889.

Application filed February 4, 1889. Serial No. 298,674. Term of patent 14 years.

To all whom it may concern:

- Be it known that I, LONGLEY LEWIS SAGENDORPH, a citizen of the United States, residing at Cincinnati, in the county of Hamilton, 5 State of Ohio, have invented and produced a new and original Design for Metallic Ceilings, of which the following is a specification, reference being had to the accompanying drawings, in which—
- 10 Figure 1 is a top plan view of a part of one sheet of ceiling, showing two panels complete; and Fig. 2 is a view of one corner of one of the panels broken away, showing a partial side view of the sheet.
  - 15 My design consists of a sheet of metallic ceiling having a series of panels, each panel consisting of a central rectangular figure made up of a series of pyramidal projections *a*, said rectangular figure being surrounded by

a border *B*, the latter having the grooved depressions *b* therein. The base of each pyramidal projection *a* is rectangular, tapering to a point, and the grooves *b* are circular in cross-section.

What I claim is—

The design for a sheet of metallic ceiling herein shown and described, consisting of a series of panels, each panel having a central rectangular figure made up of a series of pyramidal projections *a*, a border *B*, surrounding said rectangular figure, and the circular grooved depressions *b* in the border *B*, as set forth.

LONGLEY LEWIS SAGENDORPH.
